UNITED STATES PATENT OFFICE.

JEROME HAVERLY, OF BERKELEY, CALIFORNIA.

MERCURY-SEPARATOR.

1,372,137.

Specification of Letters Patent. Patented Mar. 22, 1921.

Application filed April 2, 1919. Serial No. 286,954.

To all whom it may concern:

Be it known that I, JEROME HAVERLY, a citizen of the United States, residing at Berkeley, in the county of Alameda and State of California, have invented certain new and useful Improvements in Mercury-Separators, of which the following is a specification, reference being had to the accompanying drawings.

10 This invention relates to certain improvements in mercury separators, and it is an object of the invention to provide a novel and improved device of this general character especially designed and adapted for use 15 in connection with tailings or placer material to effect a saving of the mercury and of the gold, platinum or similar values.

It is also an object of the invention to provide a novel and improved device of this 20 general character including an amalgam box having coacting therewith means for forcing the auriferous or other value bearing material below the mercury surface to assure the desired separation of the values.

25 Another object of the invention is to provide a device of this general character including novel and improved means whereby the waste material rising to the surface of the mercury is withdrawn from the amalgam box, together with means to recover and return to the amalgam box the mercury which may be withdrawn with the waste, and particularly the mercury which may be 30 directly carried by the waste.

35 An additional object of the invention is to provide a novel and improved device of this general character including a shaking or vibratory pan discharging within the amalgam box and with which coacts agitating means whereby the mercury which may be 40 delivered upon the pan in connection with the waste will be recovered.

A still further object of the invention is to provide a novel and improved device of 45 this general character including a pan leading from the amalgam box, together with means coacting with the box and pan, for withdrawing the waste from the box and carrying such waste over the pan.

50 Furthermore, it is an object of the invention to provide in connection with the amalgam box and pan novel and improved conveying means including material engaging blades reciprocating over the pan and in a 55 direction toward and from the amalgam box, together with means for raising and

holding the blades in an inoperative position during the movements of such blades toward the amalgam box.

The invention consists in the details of 60 construction and in the combination and arrangement of the several parts of my improved mercury separator whereby certain important advantages are attained and the device rendered simpler, less expensive and 65 otherwise more convenient and advantageous for use, as will be hereinafter more fully set forth.

The novel features of my invention will 70 hereinafter be definitely claimed.

In order that my invention may be the better understood, I will now proceed to describe the same with reference to the accompanying drawings, wherein:

Figure 1 is a view in top plan, with portions broken away, of a mercury separator 75 constructed in accordance with an embodiment of my invention.

Fig. 2 is an enlarged fragmentary view in side elevation of my improved separator as 80 herein embodied.

Fig. 3 is a fragmentary view in side elevation opposite to that shown in Fig. 2.

Fig. 4 is a transverse vertical sectional view taken substantially on the line 4—4 of 85 Fig. 2.

Fig. 5 is an enlarged fragmentary vertical sectional view taken substantially on the line 5—5 of Fig. 6.

Fig. 6 is a view in elevation of the lower 90 or forward end portion of my improved separator as herein embodied, the rear portion being omitted for clarity in disclosure.

Fig. 7 is a fragmentary view in top plan of the amalgam box as herein included, and 95

Fig. 8 is a sectional view taken longitudinally of the machine through the amalgam box, said section being taken substantially on the line 8—8 of Fig. 6.

As disclosed in the accompanying drawings, A denotes a substantially horizontal amalgam box of desired depth and having a rearwardly and upwardly inclined extension 1 and extending beyond the opposite ends of the box A proper. The extension 1 105 is of a depth less than the depth of the box A proper and has its upper or rear side portion free and unobstructed and defined by a depending flange 2.

Secured to the forward portions of the 110 end walls 3 of the box A are the upwardly directed standards 4 provided at their upper

ends with the boxings 5 which rotatably support the opposite end portions of a shaft 6 extending longitudinally of the box A.

The front longitudinal wall 7 of the box 5 A is provided with a plurality of spaced and inwardly directed blocks 8 to which are held by the clamps 9 the vertically disposed feed cylinders or pipes 10. The cylinders or 10 pipes 10 are open at their opposite ends and the lower end portions of said pipes extend below the mercury level *a* of the box A but are spaced from the bottom 11 of the box. The opposite or upper end portions of the feed cylinders or pipes 10 terminate a distance above the box A but below the shaft 6.

The opposite end portions of each of the feed cylinders or pipes 10 have disposed radially thereacross the members or bearings 12 which rotatably support the opposite end 20 portions of the vertically disposed shaft 14 of a spiral S. The spiral S snugly fits within the feed cylinder or pipe 10 and its direction of rotation is such as to force downwardly the auriferous or other value 25 bearing material delivered within the upper end of the cylinder or pipe 10 so that such material will be positively forced below the mercury level *a* to assure the separation of the values from the material.

30 The upper end portions of the shafts 14 are operatively connected through the medium of the bevel gears 15 with the shaft 6 so that upon requisite rotation of the shaft 6, all of the spirals S will be caused to operate in unison.

35 The shaft 6 may be driven in any desired manner, but as herein disclosed said shaft 6 has fixed to an end portion thereof a sprocket 16 over which is directed a chain 40 17. The chain 17 is also directed around a sprocket 18 fixed to the shaft 19.

45 The shaft 19 is disposed longitudinally of the box A exteriorly thereof and is supported for rotation by the outstanding bearings 20 secured to the front wall 7. The shaft 19 is adapted to be coupled in any desired manner with a suitable source of power and which connection is indicated by the sprocket 21.

50 Positioned adjacent the opposite ends of the extension 1 are the rearwardly directed and upwardly inclined beams B arranged in parallelism. The beams B may be supported in any desired manner and as this 55 forms no particular part of my present invention, it is believed that a detail disclosure of such support is unnecessary. Each of the beams B is preferably a channel rail with its open face inwardly directed.

60 Connecting the beams B and resting upon the lower flanges *b* thereof is a bottom plate or apron 22 having its forward end substantially defined by a depending flange 23 riveted or otherwise secured to the depending flange 2 hereinafter referred to. The

bottom plate or apron 22 is of a length to terminate substantially flush with the outer ends of the beams B. The side margins of the bottom plate or apron 22 are defined by the upstanding flanges 24 snugly fitting between the flanges *b* of the beams B and suitably anchored to the beams.

The forward or lower end portions of the beams B terminate in advance of the extension 1 of the box A and supported by said 75 beams for reciprocal or recurrent movement longitudinally of said beams are the spaced blades 25. Each of the blades 25 has its opposite end portions secured to the inwardly directed extensions or arms 26 carried by the spindles or stub shafts 27. Loosely mounted on the spindles or shafts 27 are the rollers 28 having direct contact with the upper flanges *b* of the beams B. Similar spindles or shafts 27 are operatively 85 connected with the pitmen or rigid links 29 so that all of the blades 25 will move in unison and in the same general direction.

The desired reciprocal or recurrent movement may be imparted to the blades 25 in 90 any desired manner but it is preferred to employ the arrangement disclosed in the accompanying drawings and wherein one of the spindles or shafts 27 of the forward or lowermost blade 25 has operatively engaged 95 therewith a rigid link 30 also operatively engaged with the sprocket 21. The second spindle or shaft 27 of the forward or lowermost blade 25 has operatively connected therewith the link 30^a also operatively engaged 100 with the rock arm 31 secured to the adjacent end portion of the shaft 19 and which rock arm 31 is provided with the balancing extension or member 32. The strokes or throw of the links 30 and 30^a are 105 the same.

The connections of the spindles or shafts 27 with the pitmen 29 are such as to permit said spindles or shafts to have rocking movement.

110 Fixed to each of the similar spindles or shafts 27 of the blades 25 and outwardly of the adjacent beam B is a rearwardly and downwardly inclined lever 33. The lower extremity of the lever 33 carries an inwardly directed pin 34 upon which is loosely mounted a roller 35 adapted to contact with the outstanding flange 36 carried by and disposed longitudinally of the beam B and which contact of the roller 35 with said 115 flange serves to operate the downward movement of the lever 33 to properly position the coacting blade during the rearward or upward movement thereof.

120 Pivotedly supported by the beam B above 125 the flange 36 and in advance of each of the levers 33, when the blades are at the limit of their forward movement, is a latch or dog 37. The latch or dog 37 is disposed downwardly and rearwardly on a desired 130

incline and which inclination is maintained or determined by the contact of said lever with the flange 36.

As the blades 25 are moved upwardly and 5 rearwardly of the beams B, the rollers 35 pass beneath the latches or dogs 37 but upon the return movement of the blades, said rollers ride upon the rear or upper edges of said dogs or latches 37 and which results in 10 the blades 25 being rocked or swung upwardly into an inoperative position. When the rollers 35 pass over the forward or pivoted ends of the dogs or latches 37, the blades drop to their normal or working position and which position, as hereinbefore 15 stated, is controlled by the contact of the rollers 35 with the flange 36.

Extending inwardly from the beams B at their opposite end portions are the 20 brackets 38 from which depend the hangers 39 supported for swinging movement in a direction laterally of the beams B. The lower end portions of the hangers 39 are pivotally engaged, as at 40, with the shaking pan P and which pan has its bottom 41 positioned in close proximity to the bottom plate or apron 22 hereinbefore referred to. The upper surface of the bottom 41 of the 25 pan P has a coating 42 of silver deposited thereon by electrolysis and for which reason 30 it is preferred that the bottom 41 be made of copper.

The second beam B or the beam not provided with the flange 36 is provided adjacent 35 its opposite ends with the outstanding bearings 43 which rotatably support a shaft 44 extending longitudinally of said beam. Mounted upon the shaft 44 are the eccentrics 45 surrounded by the straps 46 carried by 40 the outer end portions of the rigid links 47. Each of the links 47 is directed through a suitable opening 48 in the beam B and the adjacent flange 24 of the bottom plate or 45 apron 22 and either end portion of said link is pivotally engaged, as at 49, with the pan P so that as the shaft 44 rotates the pan P will be effectively shaken or vibrated.

The forward or lower bearing 43 also 50 rotatably supports a shaft 50 perpendicularly related to the shaft 44 and said shafts 44 and 50 are operatively connected, as at 51, by miter gears. The shaft 50 is driven in any desired manner and, as indicated, by the sprocket wheel 52.

55 The forward or lower end portion of the bottom 41 of the pan P is provided with a flange 53 which partially extends within the box A and projecting forwardly from said flange 53 and spaced longitudinally 60 thereof are the agitating pins 54. The rear end portion of the bottom 41 is also provided with an upstanding flange 55.

Resting upon the upper surface of the 65 bottom 41 and disposed longitudinally thereof and substantially equidistantly

spaced from said bottom 41 are the strips or cleats 56. Resting upon the strips or cleats 56 and suitably secured thereto are the cross strips or cleats 57 provided with the upstanding agitating pins 58. The strips 70 57 are spaced apart a distance to permit each of the blades with the exception of the lowermost or forward blade to have its reciprocal or recurrent movement between a pair of adjacent strips 57 or more particularly the upstanding pins 58 carried thereby.

The forward or lowermost blade 25 coacts with the amalgam box proper and operates to deliver upon the pan P the waste rising to the top of the mercury, while the remaining blades 25 operate to carry such waste upwardly of the pan to be discharged at the upper or rear end thereof. When in their normal or working position, the blades 25 are substantially at right angles to the 85 bottom 41 of the pan P.

As the waste is being conveyed upwardly of the pan P, the shaking or vibrating of said pan serves to separate from such waste any mercury which may be carried therewith and which recovered mercury will flow back into the box A. This separation of the mercury from the waste is materially facilitated by the coating 42 of silver as the mercury will immediately spread as it comes 90 in contact with said coating 42 and at once flow back into the box A. It is also to be noted that this separation of the mercury from the waste is facilitated by the agitating pins 54 and 58.

I also find it of advantage to arrange rearwardly of the feed cylinders or pipes 10 and above the box A the spray pipe 59 for the purpose of thinning the waste or tailings as the same is fed to the shaking pan.

I also find it of advantage to have pivotally engaged with the front wall c of the extension 1 and the side walls 60 of the pan P the reticulated plates 61 to prevent material and water from passing around on the outside of the pan P.

I also find it of advantage to provide the forward portion of the box A at substantially its longitudinal center with a collecting well 62 provided with a normally closed opening 63 so that the collected values or the mercury within the box may be readily withdrawn therefrom.

From the foregoing description, it is thought to be obvious that a mercury separator constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement 120 125 130

and formation of the several parts herein-
shown in carrying out my invention in prac-
tice except as hereinafter claimed.

I claim:

- 5 1. In a device of the class described, a raking mechanism comprising a pair of elongated members arranged substantially in parallelism, a plurality of transversely disposed shafts slidably engaged with said members, means for maintaining said shafts in fixed relative positions and for reciprocating said shafts, blades normally depending from said shafts, rock arms carried by the shafts and provided with lateral extensions, and inclined pivoted latches carried by one of the members, each of said latches coacting with an extension of a rock arm, said extension passing beneath the latch upon movement of the shafts in one direction and over the latch to swing the blade of the shaft upwardly during the movement of the shafts in the opposite direction.
- 10 2. In a device of the class described, a raking mechanism comprising a pair of elongated members arranged substantially in parallelism, a plurality of transversely dis-
- 15
- 20
- 25

posed shafts slidably engaged with said members, means for maintaining said shafts in fixed relative positions and for reciprocating said shafts, blades normally depending from said shafts, rock arms carried by the shafts and provided with lateral extensions, inclined pivoted latches carried by one of the members, each of said latches coacting with an extension of a rock arm, said extension passing beneath the latch upon movement of the shafts in one direction and over the latch to swing the blade of the shaft upwardly during the movement of the shafts in the opposite direction, and an outstanding flange carried by said last named elongated member and with which the extensions of the rock arms engage to limit the downward movement of the extension during the first named movement of the shafts.

In testimony whereof I hereunto affix my signature in the presence of two witnesses.

JEROME HAVERLY.

Witnesses:

ROBERT R. RUSS,
JOHN H. ROBINS.
